UNITED STATES PATENT OFFICE.

BRAINARD H. MESSERSMITH AND WILLIAM HEALY, OF YONKERS, NEW YORK.

UPHOLSTERY.

No. 888,720.

Specification of Letters Patent.

Patented May 26, 1908.

Application filed October 12, 1906. Serial No. 338,594.

To all whom it may concern:

Be it known that we, BRAINARD H. MESSERSMITH and WILLIAM HEALY, both citizens of the United States of America, and 5 residents of Yonkers, in the county of Westchester, State of New York, have invented certain new and useful Improvements in Upholstery, of which the following is a specification.

10 Our invention has for its object to provide an improvement in tufted cushions, mattresses, or similar articles whereby the buttons forming the tufts may be readily cleaned.

15 In the usual form of mattresses and cushions in which the upholstering is formed by a button drawn through and rigidly held in place, this is difficult as dirt, dust and insects get below the buttons and it is impossible to 20 remove them.

25 With our invention the buttons are held in place by elastic connection whereby they may be drawn out from the recess which they form for the purpose of cleaning them and the recesses.

30 Our invention therefore consists of the construction, arrangement and combination of the several parts of which it is composed, as will be hereinafter more fully described and claimed.

35 Referring to the accompanying drawings in which the corresponding parts are designated by similar marks of reference, Figure 1 represents a perspective view of a cushion constructed in accordance with this invention, a button being represented as drawn out for the purpose of cleaning. Fig. 2 is an enlarged detailed view showing the manner in which the button is held in place. Fig. 3 is 40 a plan of the back of a cushion showing the manner in which the elastic cord or fabric and buttons are assembled.

45 While we have represented our invention as applied to a cushion it is obvious that it is equally applicable for use in connection with other tufted articles, such as mattresses and upholstery generally.

50 As shown on the drawing the cushion A may be of any desired construction, being covered on its front face with a suitable fabric B, which is drawn into tufts by but-

tons C. These buttons consist of a suitable head portion c and the eye d, through the hole of which passes an elastic cord or fabric E, properly secured around the back 55 F of the cushion so that the button may be lifted out of the depression by extending the elastic connection.

The preferred manner of assembling the elastic cord or fabric and the buttons is to 60 firmly fasten one end of the cord or fabric to the back of the cushion, pass the other end up through an aperture therein, thread it through the eye of the button, pass it back through the aforesaid aperture and on 65 through the remaining apertures and buttons consecutively in the same manner and until all the buttons are held in place. The end of the cord is then firmly fastened to the 70 back. Thus it is evident that "a continuous elastic connection" is used to secure all of the buttons upon the upholstered article.

In an article constructed in accordance with our invention it will be seen that the buttons may be lifted by hand out of the 75 recesses formed thereby, and away from the cover, this permitting not only access to the buttons themselves, but also permitting access to the cover beneath the buttons and the removal of dirt, dust and insects therefrom.

Having thus fully described our invention what we claim and desire to secure by Letters Patent is:—

1. In a new and improved article of manufacture, an upholstered article provided with a plurality of buttons secured thereto by a continuous elastic connection, substantially as described.

2. The combination with an upholstered 90 article of a back therefor, a facing, a plurality of buttons holding the facing into tufts, and a continuous elastic connection between the back and the said buttons, substantially as described.

95 Signed at Yonkers this 18th day of August 1906.

BRAINARD H. MESSERSMITH.
WILLIAM HEALY.
